UNITED STATES PATENT OFFICE.

CHARLES J. WALZ, OF NEW YORK, N. Y., ASSIGNOR TO WEST DISINFECTING COMPANY, OF NEW YORK, N. Y., A CORPORATION OF NEW YORK.

AIR-FORCING DEVICE FOR ATOMIZERS.

SPECIFICATION forming part of Letters Patent No. 700,995, dated May 27, 1902.

Application filed March 20, 1901. Serial No. 51,968. (No model.)

To all whom it may concern:

Be it known that I, CHARLES J. WALZ, a citizen of the United States, and a resident of the borough of Manhattan, in the city and 5 State of New York, have invented a new and useful Improvement in Air-Forcing Devices for Atomizers, of which the following is a specification.

My invention relates to an air-forcing device for atomizers in which a piston is worked in a cylinder as the door is opened and closed for spraying a fluid into the surrounding atmosphere.

A practical embodiment of my invention is 15 represented in the accompanying drawings, in which—

Figure 1 is a view of the device in side elevation applied to a "full-swing" door. Fig. 2 is a top plan view of the same, the device 20 being shown in full lines in the position which it assumes when the door is closed and in dotted lines in two different positions which it assumes when the door is opened in opposite directions. Fig. 3 is a view of the device 25 in side elevation applied to a "half-swing" door; and Fig. 4 is a top plan view of the device, showing it in full lines in the position which it assumes when the door is closed and in dotted lines in the positions which it assumes when the door is opened to two different 30 positions.

The door is denoted by *a*, and it may be of any well-known or approved construction. It is hinged to the frame at *b*. The door 35 represented in Figs. 1 and 2 is a full-swing door and in Figs. 3 and 4 a half-swing door, a stock *c* being arranged to engage the free edge of the door to prevent its swinging beyond a line with the frame in one direction.

40 The cylinder *d* of the air-forcing device is supplied with a piston of well-known form operated by a piston-rod *e*, one end of which is fitted to receive a pintle *f*, uprising from the base *g* of a bracket secured to one face of 45 the door adjacent to its hinged end.

The outer end of the cylinder *d* is supported by a downwardly-turned free end of a spring-actuated arm *h*, which passes through a socket *i*, fixed to the end of the cylinder, the lower 50 end of the said arm projecting through the bottom of the socket and being there provided

with some means for retaining the arm in the socket—such, for instance, as a key *j*. The outer end of the cylinder is further provided with an air-escape nozzle *k*, to which may be 55 connected an air-tube *l*, as shown in Figs. 3 and 4, leading to some suitable atomizer. (Not shown herein.)

The spring-actuated arm *h* is hinged on a bracket *m*, fixed to the door-frame. A spring *n* normally holds the arm *h* in engagement 60 with the top of the door-frame.

When the air-forcing device is used in connection with a full-swing door, the parts are 65 so secured to the door and frame that the cylinder *d* will be free to swing beneath the top of the frame, while the arm *h* will be located in the same horizontal plane as the said top of the frame. In this construction when the door is opened in one direction the piston-rod and cylinder are positively drawn 70 apart as the piston and arm swing on their adjacent hinge. When the door is allowed to close, the movement of the piston toward the outer end of the cylinder will force the 75 air through the nozzle *k*. When the door is swung in the opposite direction, the piston will be drawn toward the inner end of the cylinder, the outer end of the cylinder at the same time swinging on its hinge connection 80 with the arm *h*, permitting the cylinder to swing beneath the top of the door-frame. In this instance also when the door is permitted to close the piston will be forced toward the outer end of the cylinder, thus forcing the air 85 out through the nozzle *k*.

In the form shown in Figs. 3 and 4, where the device is to be used in connection with a half-swing door, the parts are secured in 90 such position on the door and frame that the cylinder, as well as the arm, will be located in the horizontal plane of the top of the door-frame. In this instance the door may be opened until the piston reaches the limit of its inward movement without swinging the 95 spring-actuated arm *h*. A further outward movement of the door will cause the arm *h* to also swing outwardly on its hinge. As the door is swung inwardly from the limit of its outward movement the cylinder and arm will 100 first be put into engagement with the top of the door-frame and the piston be forced to-

ward the outer end of the cylinder for ejecting the air through the nozzle *k*.

It will thus be seen that the device, as above described, may be used to equal advantage 5 with full-swing and half-swing doors without changing the structure of the device in any particular.

It is evident that changes might be resorted to in the form, construction, and arrangement of the several parts without departing from the spirit and scope of my invention. Hence I do not wish to limit myself strictly to the structure herein set forth; but

What I claim is—

15 1. In an air-forcing device for atomizers, the combination with a door and its frame, of a swinging arm hinged to the frame, a cylinder and its piston, the cylinder-piston being hinged to the door and the cylinder being pivoted to the swinging arm, substantially as set forth.

20 2. In an air-forcing device for atomizers, the combination with a door and its frame, of a swinging arm hinged to the frame, a cylinder and its piston, the cylinder-piston being pivoted to the door and the said cylinder being at its opposite ends pivoted to and

supported by the swinging arm, substantially as set forth.

3. In an air-forcing device for atomizers, 30 the combination with a door and its frame, of a spring-actuated swinging arm normally in engagement with the frame, a cylinder and its piston, the cylinder-piston being pivoted to the door, the said cylinder being at its opposite end pivoted to and supported by the spring-actuated arm, substantially as set forth.

35 4. In an air-forcing device for atomizers, the combination with a door and its frame, a 40 bracket secured to the door, a swinging arm hinged to the door-frame, a cylinder and its piston, the cylinder-piston being hinged to said bracket, the said cylinder being pivoted to and supported by the swinging arm at its 45 outer end, substantially as set forth.

In testimony that I claim the foregoing as my invention I have signed my name, in presence of two witnesses, this 6th day of March, 1901.

CHARLES J. WALZ.
